UNITED STATES PATENT OFFICE.

WILLIAM A. C. OAKS, OF ANTRIM, NEW HAMPSHIRE, ASSIGNOR TO THE
GOODELL COMPANY, OF SAME PLACE.

APPLE PARER, CORER, AND SLICER.

SPECIFICATION forming part of Letters Patent No. 340,675, dated April 27, 1886.

Application filed May 20, 1885. Serial No. 166,108. (Model.)

To all whom it may concern:

Be it known that I, WILLIAM A. C. OAKS, of Antrim, county of Hillsborough, and State of New Hampshire, and a citizen of the United States, have invented a new and useful Improvement in Machines for Paring, Coring, and Slicing Apples, of which the following is a full and complete specification, reference being had to the drawings accompanying and forming a part of this specification.

The object of my invention is to produce a machine so constructed that while one apple is undergoing the operation of paring, coring, and slicing another apple can be placed upon the machine, ready to be acted upon when the first is completed, without stopping the revolution of the driving-wheel for an instant; in an improved quick-return motion for reciprocating knife carriage; in improved devices for pushing off the apple and the separated core; in an improved construction of the paring-knife and its supporting-rod, so that it has a double motion, to allow it to pass over irregularities on the surface of the apple; in a device for taking up the wear of the paring-knife bearings; in an improved coring and slicing knife so constructed as to be evenly supported by the cut face of the apple, and to act as a push-off for the apple when pared, cored, and sliced.

I am aware that a revolving reel with two or more forks is not new in apple-parers, as it is shown in United States Letters Patent granted to S. E. T. Dodson, dated August 4, 1874; but I obtain the rotation of my reel in a different manner, and have combined therewith devices for stopping its motion at the right point, locking it securely to prevent either forward or backward motion, and automatically releasing the reel at the right moment to present the next apple to the paring-knife.

My push-off device for removing the core of the apple consists in a central push-off rod enclosed in a hollow spindle, to which the fork is attached, and a cam or bent lever moving with a continuous rotary motion and at each revolution striking against the inner end of the push-off rod.

My improvement in the reciprocating knife-

carriage motion consists in a worm-wheel or endless-screw gearing with a spur-wheel which has upon one side a number of teeth cut away, those remaining gearing with a rack attached to the carriage and producing its motion during the cutting operation, and a system of links which act, while the blank space left by removing the teeth is passing over the racks, to effect a quick return. Four turns of the hand-crank completes the operation of paring, coring, and slicing an apple, and returns the knives to the proper position for the next apple. About three and one-quarter turns do the work, and the remaining three-fourths of a revolution of the crank brings the carriage back to its starting point, thus saving much time.

My improvement in the paring-knife consists in so constructing it that it has in addition to the usual reciprocating motion with the carriage the rocking motion at the point of support and the alternate rotary motion of knife and carriage; also, a slight motion about the axis of the knife, adapting it to pass over any irregularity on the surface of an apple; and, secondly, in a wedge-shaped piece of metal, W, which can be pushed under the heel of the knife rod, to take up the wear of the pivot-bearing, and thus keep the knife adjusted to its work. This wedge is also used to adjust the knife to the proper distance from the fork.

My improvement in the coring and slicing knife consists in adding a projecting portion below the coring-point continuous with the upper portion of the blade. This part acts to steady the blade by pressing against the cut face of the apple equally both above and below the center of the fork, and thus prevents any oblique strain bending the knife. By this means I can use a very thin-bladed knife and avoid the breaking of the spiral slices of the apple. When acting as a push-off, the pressure both above and below the center-line of the fork is especially desirable.

In the drawings, Figure 1 is a front elevation of the complete machine. Figs. 2 and 3 are detailed views of the quick-return motion, looking at it from the back. In Fig. 2 it is shown at the beginning of the return, and in Fig. 3 it is shown

at the end of the return course, ready to begin on the cutting-stroke. Fig. 4 is a side elevation of the device for rotating the reel at proper intervals and releasing the latch. Fig. 5 is a 5 side view of the bevel-wheel H, showing pawl and the ratchet-teeth which prevent the backward motion of the reel. Fig. 6 is a detail view of the latch device for keeping the reel in place while the apple is being operated upon 10 and releasing it when necessary. Figs. 7 and 8 are detail views of the push-off device. Figs. 15 9 and 10 are respectively front and edge views of the paring, coring, and slicing knife. Fig. 11 is a view of the reel, looking endwise at the forks, showing driving-pinion, fork-pinions, and also the position of the latch and the push-off lever. Fig. 12 is a side view of one fork 20 and its bearing and pinion. A portion is in section to show the details of bearing. Figs. 13 and 14 are front and side elevations of the rack with which the wheel that operates the paring-knife turn-table gears. Fig. 15 is a plan view, looking upward, of the under side of the turn-table which rotates the paring-knife. Fig. 16 is 25 a plan view of the upper surface of the turn-table, which operates the paring-knife. Fig. 17 is a detail view of the heel of the paring-knife arm, showing the arrangement of parts to permit of a slight motion about the axis of 30 the knife-arm.

A represents a table.

The machine consists of two uprights, B B', to which are secured at the top a cross-frame, B². Secured to this is a strap-bar, B³, for the 35 bearings of one of the gear-wheels. A horizontal shaft, C, to which a crank and handle, C', is attached, passes through the upper part of the frame. Upon this shaft is keyed a fast pulley, D, having teeth upon one-half the 40 width of its face, the other half being left plain for the belt when the machine is run by power.

E is a pulley running loosely on the same 45 shaft. To this pulley the belt is shipped to stop the machine when it is operated by power. The pulley D has cast upon it on one side a pinion, D', of twelve teeth, gearing with a spur-wheel, G, of forty-eight teeth. This spur-wheel has secured to one of its sides a segment 50 of ten teeth, g. This segment gears with a spur-wheel, H, of thirty-six teeth, integral with a bevel-wheel of forty-eight teeth, I, and both secured to a shaft, J. The pulley D itself has seventy-five teeth.

The spur-wheel H carries with it the shaft 55 J, which has a bearing in the uprights B B', and passes through the inner upright, B'. To the end of the shaft J the reel is attached and rotated toward the knives one-third of a revolution for each complete revolution of the wheel G. A bevel-pinion, I', of sixteen teeth, gears 60 with the bevel-wheel I, and carries with it in its rotation a bent lever, K, which, by striking against a central push-off pin in each fork-spindle, removes the apple-core from the 65 fork.

A pinion of fifteen teeth, M, gearing with the main wheel D, is keyed to a shaft, M', to

the outer end of which is secured a pinion, M², of fifteen teeth, gearing in turn with pinions M³, of like number of teeth, which are secured 70 to each of the fork-spindles. At the top of the frame a horizontal shaft, L', is fixed in suitable bearings and has secured to it a spur-wheel, L, of fifteen teeth, which acts to drive the shaft L', and thereby rotates the endless 75 screw L² at its outer end, which endless screw gears with a spur-wheel, N, of twenty teeth, which in turn gears with a rack, O, forming a part of a carriage, P, sliding upon a guide-rod, P'. Secured to the carriage is a slicing and 80 coring knife, Q, adjustably screwed to the downward-projecting part q of the carriage, and also the turn-table R, carrying the paring-knife R'. A bar, P', screwed to the frame B', has teeth cut upon a portion of its inner vertical face, to 85 produce the rotation of the turn-table R by means of a wheel with flat sides, R³.

Back of the frame-plate B² are a bent link, S, and a straight link, S², pivoted together at S³. The link S is pivoted to the frame at S⁸, 90 and the link S² is pivoted to the carriage at S⁴. A crank, S', is secured to the same shaft upon which the spur-wheel N is fast, and in its rotation strikes, by means of the pin s, against the curved face of the bent link S, and thus 95 moves the carriage in the opposite direction from that produced by the action of the spur-wheel N and rack O. To permit of this movement in a reverse direction without reversing the direction of motion of the spur-wheel N, 100 this spur-wheel N, though actually made in one piece, may be conceived to be made up of two wheels of equal diameter secured side by side upon the same axle, so as to turn together, the crank S' also turning with them. One of these 105 spur-wheels has twenty teeth, covering its entire circumference, and the other has corresponding teeth of equal pitch, but six of them are entirely cut away. The first of these wheels is in gear with the endless screw L², which 110 drives it, and the second wheel meshes with the teeth of the rack O, which is equal in width to this wheel only, and consequently is out of gear when the portion of the wheel from which the teeth are omitted is passing. During 115 the portion of a rotation during which the cut-away portion of the wheel N is passing over the rack, the carriage is free to move in either direction, and is forced by the links to move with a very rapid motion in the opposite direction from that effected by the operation of the rack, thus producing what is known as a 120 "quick-return."

The paring-knife R' is of the usual form, but with a glass guard, for which I intend to 125 make application for Letters Patent, and which, therefore, I do not describe further here, and it is attached to a bent rod, R², and a heel-piece, r, which is pivoted at r' a little back of center line of knife-arm to ears forming 130 part of the turn-table R. It is kept to its work by a spring, r², hooked to both knife-arm and turn-table. The knife-rod r² is so set in the heel-piece r that it can rotate a

small portion of a revolution on its own axis independently of the motion of the turn table. The spring r^2 serves the double purpose of keeping the paring-knife at its work and bringing the knife back to its proper position after passing over irregularities upon the apple. The spring r^2 , which yields laterally as well as lengthwise, allows the knife to rotate in the heel-piece sufficiently to pass over the 5 irregularity without difficulty or failure in its work. The knife-arm is prevented from turning too far in either direction by a pin, r^3 , in the end of the arm, and stops formed by the sides of the recess in the heel piece r . This 10 pin acts, also, to prevent the arm being withdrawn from the heel-piece.

The necessary rotary motion of the turn-table is effected by a spur-wheel, R^3 , with two parallel flat portions, r^4 , on which there are 20 no teeth. The end teeth, r^5 , are made longer, so as to readily enter into gear with the rack cut on the inside of the bar P' and to keep the wheel from turning while passing the smooth face of the spaces. At the beginning and end 25 of the rack the teeth are also deeper, to permit the long teeth to enter. The spur-wheel R^3 is securely attached to the turn-table R , and when in place gears with the rack P' , which forms a part of the frame of the machine. As 30 the carriage advances or retreats, the turn-table is forced to revolve uniformly by means of the teeth until it reaches a flat side, when it remains stationary, the knife meantime not rotating.

35 The slicing and coring knife Q is similar to those in general use for such purposes, except in the important particular that it has below the coring-point q' a projecting portion, q^2 , integral with and in the same plane as the 40 rest of the blade. This lower portion of the knife, by bearing on the cut surface of the apple below the center line of the fork, and thus avoiding oblique or bending strain, enables me to use a thin blade, which is desirable, be- 45 cause a thick blade will break up the apple. The bearing above and below also enables me to use the knife as a push-off.

The reel mechanism consists of a shaft, J , driven intermittently by means of the toothed 50 are g , forming part of the spur-wheel G , which is driven by the main wheel and crank, and a face-plate, T , having cast with it three journal-bearings, $T' T' T'$, with one half of each removable. A brass journal-box or bushing, t , 55 is inserted in each, and through each of these bushings or boxes a hollow spindle, t^2 , passes, bearing on its outer end a fork. The collar of the fork is recessed at its inner end, so that the bushings run under it a short distance, to 60 keep out dust, apple juice, &c. Through the center of each hollow spindle a push-off rod, t^3 , passes, the ends enlarged to hit against the apple-core and the push off lever. At the inner end of each spindle is also secured a spur- 65 wheel of fifteen teeth, M^3 , which can mesh with a spur-wheel, M^2 , driven by the main driving-wheel. The reel is prevented from

advancing in the direction of its rotation beyond the proper point by a latch, V , operated by a lever, V' , and spring V^2 , which lever is 70 hit upon its inner end by a pin, g^2 , on the wheel G once each revolution, forcing the inner end out against the spring V^2 , and as it is pivoted at V^3 the outer end of latch V recedes and allows the reel to turn forward. The spring 75 V^2 forces the latch back again into place, locking the reel during the operation of paring, &c. The rack is prevented from turning backward by a pawl, H^2 , which passes over the edge of the wheel I , and falls into ratchet-teeth cut at three equidistant points in its circumference. W is a thin wedge-shaped piece of metal screwed to the turn-table R , so that it can be pushed more or less under the heel of the knife to adjust it to its proper position 85 in regard to the forks.

The absolute numbers of teeth in each wheel may vary from those given above, but to make the various parts of the machine work in proper time they should be in the same relative position. 90

The operation of the machine is as follows: An apple is placed upon the fork which is in front and on a horizontal line with the axle of the reel. The crank is then turned over and to 95 the right, in the direction indicated by the arrow, until the latch is withdrawn and the apple is brought in front of the paring-knife. The latch slips into place, preventing the reel from moving farther forward. At the same time a 100 pawl, H^2 , resting upon the periphery of the bevel-wheel I , drops into one of the notches h , cut at three equidistant points. This prevents the reel turning backward. The reel being locked in position, and the crank being still 105 rotated, the driving-wheel D , meshing with the pinion L , turns with it the endless screw L^2 , at each revolution moving the wheel N in the direction of the arrow one tooth, and this, gearing with the rack P , pulls the knife toward the 110 apple. The wheel which is attached to the upper side of the turn-table R , and which has two flat sides, commences to mesh with the rack cut on the inside of the bar P' , and thus rotates the turn-table, carrying with it the paring-knife, 115 which thus turns in the usual way around the contour of the apple. As it advances, any irregularities on the surface of the apple are pared evenly by means of the small motion which the knife arm has about its own axis, being brought into normal position after the irregularity has been passed over. The paring-knife having nearly completed its work, the carriage still continuing its motion toward the forks, the slicing-knife begins to act and cuts 120 the apple into a continuous spiral, at the same time coring it. The carriage having now reached the limit of its course in one direction, the fourteen teeth on one side of the wheel N have all passed, leaving the space in 125 which six teeth are omitted, and the rack, being entirely free to slide upon the guide-rod P^2 , is forced backward by means of the levers $S S^2$ and the crank S' , attached to the end of

the axis of the wheel N, which at this time is in the position shown in Fig. 2. The return-motion is effected in about one quarter the time required for the cutting-stroke of the carriage, the quick return occurring during the time required to rotate the wheel N through the space of six teeth, fourteen teeth effecting the forward motion. During the forward or cutting-stroke of the carriage the wheel G is turning and carrying with it the toothed arc or segment g toward the spur-wheel H. At the same time the bent lever K, attached to the wheel I', swinging around and passing through a slot in the frame B', has hit the push-off pin t^3 , and pushed the core from the fork, the apple having been previously removed by the slicing-knife during the quick return of the carriage. The apple and core being out of the way, a new apple is placed upon the front fork, the latch is withdrawn by the pin g^2 on the wheel G, the toothed segment or arc g comes into gear with the spur-wheel H, and, having ten teeth to the thirty-six teeth of the latter, advances the wheel H, and with it the reel, one-third of a revolution, bringing a new apple into position for cutting, when the operation goes on as before, each four complete turns of the crank paring, slicing, coring, removing the apple and core, and bringing the parts of the machine into position to begin upon the next apple.

k is the cam portion of the bent lever K.

The fork-bearings consist of a hollow spindle, t^2 , through which the push-off rod t^3 passes easily, inclosed in a piece of brass tube, t , which in its turn rests in the outer journal-box, T, made in halves, the portion T^2 being removable and held in place by screws which clamp the brass-bearing securely in place.

Having now fully described my invention, what I claim, and desire to secure by Letters Patent, is—

1. In an apple-paring machine, an improved device for successively bringing the apples in front of the knives and holding them there long enough to complete the operations of paring, coring, and slicing, consisting of a revolving fork-bearing reel, in combination with a toothed arc driven intermediately from the crank-axle, a latch for preventing the reel moving too far forward, and a pawl pressing against the notched edge of a wheel secured to the shaft, to which the reel is also secured, all substantially as shown and described.

2. The combination, with the paring-knife carriage provided with a rack, O, and mounted to reciprocate in suitable guides of the frame, of the worm-shaft L', connected with the driving gearing, and having worm L², worm-wheel N, gearing with rack O, and having a portion of its teeth cut away, as described, bent lever S, pivoted to the machine-frame, link S², pivoted to said lever and to the knife-carriage,

and the crank S', carried by the shaft of the worm-wheel N, substantially as described. 65

3. The combination, with the reel provided with a series of fork-shafts, each having a central doffer-pin and mechanism for intermittently rotating the reel, of the curved cam-lever K, bevel-pinion I', to which said lever is attached, and a gear for operating said pinion, substantially as described.

4. An improved coring and slicing knife for an apple-paring machine, having a portion of the main blade of the knife projecting below 75 the coring-prong, for the purpose of forming an even bearing against the apple, as set forth and described.

5. In an apple-paring machine, the combination of a paring-knife and its supporting-arm with a heel piece in which the supporting-arm can turn freely through a small arc, having its own axis for a center, the said motion being limited by a pin in the arm under the heel-piece abutting against stops or the 85 sides of a recess, and a spiral spring attached to projecting points of both knife-arm and turn-table, operating to keep the arm in the central position of its possible motion, all constructed substantially as shown and de- 90 scribed.

6. In an apple paring machine, the combination of the paring-knife arm and heel r with the turn-table R and a wedge-shaped piece of metal, W, screwed to the turn-table, 95 so that it may be pushed more or less under the heel of the knife-arm for adjustment, all substantially as and for the purpose specified.

7. The combination of the intermittently-revolving fork-bearing reel T with the reciprocating knife-carriage P, driven during the cutting-stroke by a rack, O, and pinion N, and during its return-stroke by a combination of links, S S², operated by a crank, S', upon the axis of the wheel N, all substantially as 105 shown and described.

8. In an apple-paring machine, the combination of the driving-pulley D, intermediate gears, D' and G, revolving fork-reel T, intermittently rotated by a toothed arc, g , and held 110 in place by the pawl H² and automatic latch V, the paring-knife R', rotating with the turn-table R and reciprocating on the guide P² by means of the pinion L, shaft L', endless screw L², spur-wheel N, and rack O, the improved 115 quick-return mechanism consisting of the lever S, link S², and the crank S', coring and slicing knife Q, and the push-off device K, all substantially as shown and described.

In witness whereof I have hereunto set my 120 hand.

WILLIAM A. C. OAKS.
